US0D1054518S

(12) United States Design Patent (10) Patent No.: US D1,054,518 S
(45) Date of Patent:  Dec. 17, 2024

(54) FRAME OF FOLDING TENT

(71) Applicant: Wuyi Letu Leisure Products Co., Ltd,
Jinhua (CN)

(72) Inventors: Xin Qiu, Jinhua (CN); Huakai Pan,
Jinhua (CN); Xuanyin Tao, Jinhua (CN)

() Term: 15 Years

(21) Appl. No.: 35/516,449

(22) Filed: Feb. 15, 2023

(80) Hague Agreement Data

Int. Filing Date: Feb. 15, 2023

Int. Reg. No.: DM/226973

Int. Reg. Date: Feb. 15, 2023

Int. Reg. Pub. Date: Mar. 3, 2023

(30) Foreign Application Priority Data

Nov. 28, 2022 (CN) 202230795230.7

(51) LOC (14) Cl. 21-04

(52) U.S. Cl.

USPC D21/839

(58) Field of Classification Search
